UNITED STATES PATENT OFFICE

CALVIN C. MCGAUGH, OF ELK CITY, OKLAHOMA

HOSIERY DISPLAY CABINET

Application filed February 15, 1930. Serial No. 428,699.

The present invention relates broadly to display cabinets and the primary object of the present invention is to provide certain new and useful improvements in display cabinets of a type embodying the subject matter of my co-pending application, Serial No. 373,540 filed by me under date of June 25, 1929.

With the above and numerous other objects in view, the present invention consists of the peculiarities of construction, combination and arrangement of parts more fully described, and set forth in the appended claims.

In the drawings:

Figure 1 is an elevational view of the display cabinet looking at the same either from the front or rear,

Figure 2 is a side elevational view thereof,

Figure 3 is a horizontal transverse sectional view taken substantially on the line 3-3 and looking downwardly in the direction of the arrows,

Figure 4 is a longitudinal vertical sectional view therethrough,

Figure 5 represents a vertical detail sectional view through a portion of the cabinet showing the display compartments illuminating means therefor.

Figure 6 represents a fragmentary corner elevation of the cabinet at the upper portion of the cabinet.

Referring to the drawings, it will be seen that the invention includes a base 5 a pair of perpendicular side walls 6-6 and a top 7. A pair of partitions 8 and 9 separate the cabinet into three main sections. In the sections below the partition 9 is a vertical partition 10 dividing said section into a front and rear compartment. In the section above the partition 9 are the vertical walls 11-11 extend in parallelism to the side walls 6.

A partition 12 connects the said vertical walls 11 and divides the said section into a front and rear compartment. The section above the partition 8 provided with a pair of vertical walls 13-13 and a vertical partition 14 connecting the said vertical walls 13-13 beside the last referred to section into front and rear compartments.

In the compartments on each side of the partition 10 are horizontal shelves 15 connecting the side walls 6. Between the partitions 8 and 9 are shelves 16 connecting the vertical walls 11-11 on opposite sides of the partition 12. In the sections between the partition 8 and top 7 and arranged on opposite sides of the partition 14 are shelves 16 connecting the vertical walls 13. Thus it will be seen that at the front and rear thereof the cabinet is in duplicate.

Each of the side walls 6 above the partition 9, and above and below the partition 8 are provided with transversely extending openings 18 and 19 respectively. The side walls 6-6 at each end of the openings 18 and 19 are provided with vertically extending slots 20 and insertable through the slots for closing the openings are transparent panels 21. The space between the panels 21 and adjacent vertical walls 13 respectively provide above and below the partition 8 display compartments in which are mounted hosiery covered limbs. The panels 21 and respective adjacent vertical walls 11 and 13 constituting side walls of these display compartments.

Transparent panels 22 are disposed between the side walls 6 and adjacent vertical walls 11 and 13 at each end of the display compartment for closing the front and rear ends of these compartments.

Receivable in the spaces on opposite sides of the partition 14 between the top 7 and the uppermost shelves 16 are drawers 23. Obviously, the drawers 23 may be used for containing various papers relative to the stock arranged in the cabinet, the nature and amount of sale, etc.

From the foregoing then it will be appreciated that I have evolved a hosiery display cabinet wherein the several compartments of the cabinet are easily accessible, the hosiery advantageously displayed, and at the same time the cabinet being fully capable of such construction as to provide only a useful but attractive article of store furniture.

Arranged in each of the upper and lower display compartments adjacent the panels 21, and at the upper forward and rear ends of

said compartment are suitably mounted electric light bulbs 24 with which are associated suitable reflectors 25. Suitable electrical connections are provided for supplying current 5 to the bulbs one of the electrical connections 27 being arranged in the base 5, and the other electrical connection 28 being mounted on the top 7. Thus is provided suitable illumination for each of the display compartments for 10 more effectively displaying the hosiery arranged therein.

It may be also noted, that the side walls 6-6 having the lower portions thereof disposed between the base 5 and partition 9 suitably panelled as at 29, the panels 29 being preferably of wood.

Even though I have herein shown and described the preferred embodiment of my invention, it is to be understood that the same is 20 susceptible to changes fully comprehended by the spirit of the invention as herein described, and the scope of the appended claims.

Having thus described my invention, what I claim as new is:

25 1. A hosiery merchandising and display cabinet comprising a base, shelves surmounting the base and open at opposite sides thereof, display compartments above the said shelves located at opposite sides of the cabinet 30 and each enclosed by glass panels arranged at right angles to each other, to expose the interior of each compartment from three sides of the cabinet, each compartment having a height sufficient to accommodate and display 35 a full length stocking form, and additional shelves located between the said display compartments and opening at opposite sides of the cabinet, said shelves being adapted to receive and support boxes of hosiery such as 40 displayed on the forms.

2. A hosiery merchandising and display cabinet comprising a base, shelves surmounting the base and open at opposite sides thereof, display compartments above said shelves 45 located at opposite sides of the cabinet and each enclosed by glass panels arranged at right angles to each other, to expose the interior of each compartment from three sides of the cabinet, each compartment having a height sufficient to accommodate and display 50 a full length stocking form, additional shelves located between the said display compartments and opening at opposite sides of the cabinet, said shelves being adapted to receive and support boxes of hosiery such as 55 displayed on the forms, and means whereby at least one of the glass panels of each display compartment may be moved to permit access thereto.

60 3. A hosiery merchandising and display cabinet comprising a base, shelves surmounting the base and open at opposite sides thereof, display compartments above the said shelves located at opposite sides of the cabinet 65 and each enclosed by glass panels arranged

at right angles to each other, to expose the interior of each compartment from three sides of the cabinet, each compartment having a height sufficient to accommodate and display a full length stocking form, additional 70 shelves located between the said display compartments and opening at opposite sides of the cabinet, said shelves being adapted to receive and support boxes of hosiery such as displayed on the forms, and a longitudinally 75 slotted corner post at a corner of each display compartment and through which one of the glass panels may slide laterally to permit access to the compartment.

In testimony whereof I affix my signature. 80
CALVIN C. McGAUGH.
